UNITED STATES PATENT OFFICE.

LUIS KOBUCHI, OF SMITHFIELD, PENNSYLVANIA.

PROJECTILE.

1,330,079.

Specification of Letters Patent. Patented Feb. 10, 1920.

Application filed August 21, 1919. Serial No. 319,023.

To all whom it may concern:

Be it known that I, LUIS KOBUCHI, a citizen of Italy, residing at Smithfield, in the county of Fayette and State of Pennsylvania, have invented certain new and useful Improvements in Projectiles, of which the following is a specification.

The primary object of the present invention resides in the provision of a projectile embodying a plurality of arms swingingly attached thereto in which the outer faces of the arms normally housed within the outer faces of the projectile are provided with forwardly directed saw teeth, the projectile being especially adapted for firing through barbed wire entanglements for severing the same.

A further object of the invention is to provide a projectile having normally retracted arms contained within the sides of the projectile body that are adapted to be swung outwardly from the discharge of the projectile from the gun muzzle having combined therewith high explosive mechanism for firing by a time fuse after the arms have functioned in severing barbed wire entanglements and the projectile reaches its destination.

With the above and other objects in view that will appear as the nature of the invention is more fully understood, the device consists of the novel construction and arrangement of parts to be hereinafter more fully described and then claimed, reference being had to the accompanying drawing by like characters designating corresponding parts throughout the several views, in which,

Figure 1 is a perspective view of a projectile constructed in accordance with the present invention, the saw arms being projected therefrom,

Fig. 2 is a longitudinal sectional view with the saw arms in a retracted position, the position assumed by the projectile while in a gun tube, and

Fig. 3 is a view similar to Fig. 2 with the saw arms projected,

Briefly described, the present invention aims to provide a projectile having longitudinal grooves formed at the sides thereof and opening at the outer face, with an arm pivotally mounted at its forward end in the forward ends of the slots and adapted to be projected outwardly by tensioned levers slidably associated with the arms and be so

retained in an outward position while the outer edges of the arms are provided with forwardly directed saw teeth adapted for severing barbed wire entanglements or similar devices during its forward travel toward its destination and having combined therewith a time fuse for rendering the same highly explosive at the desired time.

Referring more in detail to the accompanying drawing there is shown a projectile of the usual formation embodying a body portion 5 having a central chamber 6 to contain shrapnel or high explosive with forwardly positioned firing mechanism 7 therefor, the details of which firing mechanism do not enter into the gist of the present invention, as any other appropriate form or fuse or firing device for the explosive contained within the chamber 6 could be employed.

As clearly illustrated, the outer faces of the projectile body 5 are provided with a plurality of spaced longitudinally extending grooves 8 that open at the outer sides of the body 5 and have pivoted therein arms 9 mounted upon the pins 10 secured adjacent the forward ends of the grooves 8, arms 9 when in their retracted positions as shown in Fig. 2 being entirely housed within the grooves 8. Means is provided for projecting arms 9 and includes a lever 11 pivoted as at 12 in the rear end of each groove 8 and has a hook 13 at its forward swinging end adapted for sliding reception in the longitudinal slot 14 provided in the arm 9, the rear end of the slot 14 having an offset recess 15 at the rear end thereof adapted to receive the hooked end 13 of the lever 11 when the arms are projected to their full extent to be seated therein and prevented from returning to their initial positions in the slots 14 thus to hold the arms 9 distended as indicated in Figs. 1 and 3. The bottom wall of each recess 8 is provided with a socket 16 adjacent the rear end thereof and is adapted to receive an expansion

coil spring 17 the outer end of which is secured to the lever 11 as at 18, the springs being held under compression with the arms 9 retracted within the body of the projectile while the projectile is within the gun tube.

The operation of the device is believed to be plainly obvious, it being noted that immediately upon the discharge of the projectile from the gun tube, the springs 17 will force the levers 11 outwardly which motion

is communicated at the pivoted arms 9 until the hooks 13 of the levers reach the rear ends of the slot 14 at which time the forward movement of the projectile will cause the arms to swing rearwardly for the seating of the lever hooks in the recesses 15, thus locking the arms 9 in their outward distended positions. As illustrated, the arms 9 have their outer faces provided with saw teeth 9' rendering the projectile highly serviceable in the severance of barbed wire entanglements or in fact any other obstructions with which the arms of the projectile might come into contact while the time fuse may be set to cause an explosion of the projectile at any desired time. The present device may be made in many different sizes and is capable of use with small arms or ordnance.

20 While there is herein shown and described the preferred embodiment of the invention,

it is to be understood that various changes may be made as will fall within the scope of the invention as claimed.

What is claimed as new is:—

25 A projectile comprising a body portion provided with a plurality of longitudinally extending spaced grooves, an arm having a saw edge pivoted in the forward end of each groove, each of said arms having a longitudinal slot therein with an offset recess at the rear end of each slot, a lever pivoted in the rear end of each groove and having a sliding connection at its free end with the groove in said arm, and a spring associated 30 with each lever for forcing the same outwardly and into position whereby said lever is received in the offset recess of said slot to prevent the closing of the arms.

35 In testimony whereof I affix my signature.

40 LUIS KOBUCHI.
